UNITED STATES PATENT OFFICE.

CYRIL SAMUEL DRAYTON PERRY, OF PORT ARTHUR, ONTARIO, CANADA.

BOILER SUPERHEATER.

Application filed March 29, 1921. Serial No. 456,615.

To all whom it may concern:

Be it known that I, CYRIL SAMUEL DRAYTON PERRY, of the city of Port Arthur, in the Province of Ontario, Canada, have invented certain new and useful Improvements in Boiler Superheaters, of which the following is the specification.

The invention relates to improvements in boiler superheaters and an object of the invention is to provide a superheater particularly designed for use in a marine boiler which will effectively superheat the saturated steam of the boiler and deliver it to the engine supply pipe in a superheated state, thereby materially increasing the efficiency of the boiler and engine.

A further object of the invention is to construct the superheater so that it can be readily applied to the existing type of marine boiler without requiring alterations in the construction of such boiler and to arrange the appliance so that it can be readily installed in similar units corresponding to the number of furnaces in the boiler.

A further object of the invention is to construct the headers of the superheating units such that they are interchangeable and such that the connections between headers can be readily made.

With the above more important and other objects in view the invention consists essentially in a pair of headers located in each combustion chamber of the boiler, superheating coils connecting the headers, a distributing connection connected to the saturated steam pipe of the boiler, branch distributing pipes leading from the connection through the boiler to a superheater in each combustion chamber, a collecting connection associated with the superheated steam pipe and collecting branch pipes passing through the boiler and connecting the latter connection with the other header of each furnace, the parts being arranged and constructed as hereinafter more particularly described and later pointed out in the appended claim, reference being had to the accompanying drawings in which:—

Fig. 1 is a front end view of a marine boiler showing my invention applied there-

on, the customary smoke pipe being removed.

Fig. 2 is a vertical sectional view through the boiler, the section being taken at 2—2 Fig. 1.

Fig. 3 is an enlarged vertical sectional view transversely through the upper part of the boiler and looking forwardly, the section passing through the upper parts of the combustion chambers to the rear of the 60 headers.

Fig. 4 is an enlarged detailed side view of one of the headers.

Fig. 5 is an enlarged detailed end view of one of the headers.

Fig. 6 is a vertical sectional view through one of the headers.

Fig. 7 is an enlarged detailed vertical sectional view through the distributing connection.

Fig. 8 is an enlarged detailed vertical sectional view through the joint connecting the superheater coil with the header.

In the drawings like characters of reference indicate corresponding parts in the 75 several figures.

I have shown the invention as installed on what is known as the cylindrical or "Scotch" boiler which is the type almost exclusively adopted in merchant service. I 80 have not considered it necessary to give a detailed description of such boiler as it is well known.

The said boiler consists of a cylindrical shell 1 with which flat ends 2 and 3 are 85 stayed together by long tie rods 4. The furnaces vary in number and in the present instance I have shown three indicated at 5, 6 and 7 and the furnaces are supplied with the customary grates and pass from the front plate rearwardly to the combustion chambers 9, 10 and 11. The combustion chambers are vertically disposed and are completely enclosed in the cylindrical shell and are entirely surrounded by water. 90 Smoke tubes 12 pass from each combustion chamber back to the front plate of the boiler and through the water of the boiler and communicate with the smoke uptake (not shown) which leads to the funnel. 95

The pipe 13 communicates with the boiler and contains saturated steam. This pipe leads to the front end of the boiler where it is turned downwardly and is supplied 5 with an outstanding coupling flange 14.

15 is a superheated steam pipe for supplying steam to the engine. This pipe also leads from the front end of the boiler and is supplied at the front end with a coupling 10 flange 16. To the front end of the pipe 13 I connect a distributing connection 17 which is provided with an outstanding flange similar to that 14 and is fastened to the pipe by bolting through the flanges. To

15 the forward end of the pipe 15 I connect a collecting connection 18 which is provided with an outstanding flange 19 bolted to the flange 16. The distributing and collecting connections communicate in each instance 20 with the same number of branch pipes, the number of the branch pipes depending entirely on the number of the furnaces of the boiler. In the present instance I have shown three furnaces so that there 25 are three distributing branch pipes 20, 21 and 22 connected to the distributing connection 17 and three collecting branch pipes 23, 24 and 25 connected to the connection 18.

30 In the upper part of each combustion chamber of the boiler I locate a pair of headers 26 and 27, the headers being connected by coils of pipe 28. The header 27, which is the receiving or lower header, is in a 35 lower plane than that of header 26. The headers are all identically constructed, being substantially rectangular and box like and they are provided at their opposite sides with upper and lower rows of bosses 40 29 and 30, the bosses of the rows being staggered in position and are fitted at their forward ends with a boss 31 which is cored and screw threaded to receive the rear end of one of the branch pipes herein before mentioned.

45 By providing both sides of the headers with bosses they can be used as desired, either right or left, as it is only necessary to core out and screw thread the bosses at one 50 side or the other when the header is to be inserted. The headers are supported in the upper part of the combustion chamber by brackets 32 and 33 permanently fastened to the inner wall of the combustion chamber.

55 The coils of pipe 28 which connect the headers of each combustion chamber are of a flattened S-shape and are arranged in upper and lower groups, there being a number of lower coils connecting the lowermost

60 openings of the header 27 with the lowermost openings of the header 26 and a number of higher coils connecting the upper openings of the header 27 with the upper openings of the header 26. Here I wish it 65 to be understood that the openings of the

headers to which I refer are the openings formed by coring and screw threading the bosses of the headers.

It is necessary to maintain a tight joint between the pipe coils and the headers and I have found it advisable to use ball jointed union joints with copper faces, the form of joint being best shown in Fig. 8 wherein it will be seen that the socket like member 34 receives the ball faced member 35, the members being held permanently seated by a jam nut 36. The details of the latter joint however are not essential as any joint which will withstand conditions can be used.

In Fig. 3 it will be seen that there is a pair of headers in each combustion chamber. The lower headers communicate with the branch pipes 20, 21 and 22 whilst the upper headers communicate with the branch pipes 23, 24 and 25. Accordingly, it will be apparent that the saturated steam coming from the boiler through the pipe 13 and entering the connection 17 is distributed through the distributing branch pipes to the lower headers and passes from the lower 90 headers through the groups of coils to the upper headers and from the upper headers is returned as superheated steam through the collecting branch pipes and collecting connections to the pipe 15, which is the service pipe, to the engine.

The branch pipes in all instances pass through selected smoke tubes, being somewhat less in diameter than the smoke tubes.

From the above it will be obvious that each combustion chamber contains what might be called a superheating unit embodying the headers and connecting coils and that these units are all identical. Accordingly it is a very easy matter to equip a boiler with my superheater as one simply provides a superheating unit for each combustion chamber and then makes the connections through the branch pipes to the saturated and superheating steam pipes. The connections 17 and 18 would require to be changed to accommodate the number of furnaces of the boiler but otherwise the installation is not affected by the number of furnaces.

Obviously the saturated steam admitted will be superheated in the coils by the intense heat developed in the combustion chambers and accordingly I not only effect a big saving of fuel but have high efficiency of power and practically no moisture at the engine between pistons and cylinder, valves and chests, which is a difficulty now experienced.

What I claim as my invention is:—

The combination with a boiler having a plurality of furnaces of a super-heater for each furnace comprising a pair of elongated hollow casings supported in the upper part and on opposite sides of the furnace fire box,

one of said headers constituting the delivery header and being positioned somewhat higher than the other or receiving header, a plurality of rows of S-shaped super-heating coils connecting the headers of each pair, the coils of one row being located between the coils of the adjoining row, a saturated steam supply pipe, a plurality of distributing conduits extending between said 10 supply pipe and the receiving headers of

the super-heaters, a super-heated steam conduit, and a plurality of pipes extending between said last mentioned conduit and the delivery headers of the super-heaters.

Signed at Port Arthur, this 12th day of 15 February 1921.

CYRIL SAMUEL DRAYTON PERRY.

In the presence of—

W. F. LANGWORTHY,
W. A. McCALLUM.
